UNITED STATES PATENT OFFICE.

PETER C. FRITZ, OF PHILADELPHIA, PENNSYLVANIA.

WASHING MACHINE.

Application filed March 31, 1920. Serial No. 370,070.

To all whom it may concern:

Be it known that I, PETER C. FRITZ, a citizen of the United States, residing at Philadelphia, in the county of Philadelphia 5 and State of Pennsylvania, have invented new and useful Improvements in Washing Machines, of which the following is a specification.

My invention relates to a new and useful improvement in washing machines, and has for its object to provide an exceedingly simple and effective machine of this description which when in operation will not only pound the clothes being washed, but by 15 permitting the escape of air from the beaters upon their downward movement will draw water through the clothes by suction, thus subjecting the clothes to a double cleansing action.

20 A further object of my invention is to provide for so balancing the beating element and their valve mechanism between the springs as to provide a cushioning action while making the operation of the 25 parts positive.

A further object of my invention is to so construct the beaters that they will have an intense though not injurious action upon the clothes for cleaning the same.

30 A further object of my invention is to provide for a step by step revolving of the beaters whereby they will be brought into contact with the clothes at different points upon each downward stroke.

35 A still further object of my invention is to provide for the last named action by a simple and effective mechanism contacting with the actuating pitman.

With these ends in view, this invention 40 consists in the details of construction and combination of elements hereinafter set forth and then specifically designated by the claims.

In order that those skilled in the art to 45 which this invention appertains may understand how to make and use the same, I will describe its construction in detail, referring by numerals to the accompanying drawings forming a part of this application,

50 in which:-

Fig. 1, is a plan view of a washing machine made in accordance with my improvement, a portion of the cover being broken away to show the location of the beaters 55 therein.

Fig. 2, in a side elevation of Fig. 1, a portion of the machine being broken away and sectioned to show the interior mechanism.

Fig. 3, is an enlarged view of a portion of the machine partly in section and partly 60 in elevation, to clearly show the construction and operation thereof.

Fig. 4, is an elevation taken at right angles to Fig. 3, the receptacle being omitted.

Fig. 5, is a detail view of the ratchet 65 mechanism for imparting an intermittent step by step movement of the beaters.

Fig. 6, is a detail view of the beaters.

Fig. 7, is an edge view thereof, one of the beaters being in section. 70

Fig. 8, is a bottom plan view of Fig. 6.

In carrying out my invention as here embodied, 1 represents a receptacle adapted to contain the clothes and water for washing the same and may be of any desired 75 shape or size, and this receptacle is supported by the legs 2 and from the underside thereof depends the casing 3 in which is journaled a shaft 4 carrying the worm 5 which meshes with the worm wheel 6 secured 80 upon the shaft 7 which latter projects through a suitable bearing 8 in the side of the casing.

The worm wheel 6 has a crank pin 9 projecting from one side thereof to which is 85 attached the lower end of the pitman 10, the upper end of said pitman terminating in a ball head 11 which fits within a suitable socket formed within the head 12, said ball being held in place by the sleeve 13 threaded 90 upon said head so as to produce a ball and socket joint.

14 represents the actuating rod which passes through the bottom of the receptacle 1 and also through the ratchet wheel 15, 95 the hub 16 of said ratchet wheel being journaled in the bearing 17 secured to the underside of the receptacle. This actuating rod has a spline groove 18 formed in the lower portion thereof into which fits the key or spline 19 so as to cause said rod to revolve with the ratchet wheel and yet permit its free movement up and down through the latter as will be readily understood.

The revolving of the ratchet wheel 15 100 is accomplished by a spring actuated pawl 20 carried by the pawl rod 21 which in turn is pivoted at 22 to the lever 23. The lever 23 is formed with or secured to the rock shaft 24, which latter is pivoted in suitable 110

bearings carried by the casing 3, and this rock shaft has a depending lever 25 the lower end of which carries a striker pin 26 for the purpose next explained. As the 5 worm gear 6 is revolved in the direction of the arrow marked thereon the pitman will come in contact with the striker pin 26 causing the lower end of the lever 25 to be carried with said pitman through one-half 10 of the revolution of the worm gear thereby actuating the pawl 20 to revolve the ratchet wheel 19 which in turn will revolve the rod 14. The other half of the revolution of the worm gear 6 carrying the pitman in the 15 opposite direction will permit the lever 25 to swing backward thereby permitting the pawl 20 to slide over the teeth of the ratchet in a reversed direction for the further engagement and actuation of said ratchet as 20 will be readily understood.

27 represents a yoke which is adjustably secured upon the actuating rod 14 by means of the set screw 28 so that this yoke may be set higher or lower upon said rod, and 25 each of the outer ends of this yoke carries a tubular housing 29 adapted to fit over and slide upon a hub 30. The housings 29 are soldered, brazed, welded or otherwise secured to the yoke 27. The hubs 30 are 30 formed with or secured to the beaters 31, and these beaters are here shown as a pair united by the cross bar 32 in which latter is formed an opening 33. 34 represents a tube which is secured to the bottom of the 35 receptacle 1 through which the actuating rod 14 passes, said tube serving as a support and bearing for said rod in the up and down and rotary movements of the latter, said tube also serving as a guide for the 40 cross bar 32 and passing through the opening 33 in said bar as clearly shown in Fig. 3. In each of the beaters is formed a valve seat 35 against which the valves 36 are adapted to close, and each of these valves 45 is provided with a stem 37 which extends upward through the hubs 38 formed upon the outer ends of the yoke 27, said hubs serving to guide said stems. In lieu of forming the hubs 38 with the yoke 27 they 50 may be made of separate pieces and soldered or welded thereto.

55 A spring 39 is coiled around the lower portion of each of the valve stems, the lower end of said springs bearing upon the valves 36 so as to tend to force said valves downward from off their seats, while a spring 40 is coiled around the upper portion of each of the valve stems, and these last named springs being stiffer or of 60 greater tension than the first named springs their upper ends bearing against the washers 41 secured upon the valve stems by the pins 42.

65 The beaters 31 are of peculiar shape and construction especially adapting them for

the work to be performed, each of said beaters being shaped in plan the underside thereof being concaved and being provided with a longitudinal rib 43 and cross ribs 44 thus making a framework adapted to 70 strike the clothes being washed in such a manner as to effectively loosen the dirt therein.

A bearing 45 is formed in the ribs of each of the beaters for the passage of the 75 lower ends of the valve stems 37, thus giving a further guidance to said stems.

From the foregoing description the operation of my improvement will be obviously as follows:—

80 The actuating rod being reciprocated and rotated as before described by the revolving of the worm gear 6 the beaters will be moved up and down and at the same time rotated intermittently step by step within the receptacle, and this up and down movement of the beaters will cause them to come in violent contact with the clothes placed within the receptacle, and when pressed against said clothes with sufficient force 90 to overcome the tension of the springs 37 said beaters will be arrested in their downward movement while the yoke 27 continues to move downward which will compress the springs 37 sufficiently to overcome the 95 action of the springs 40 thereby forcing the valves 36 from off their seats permitting the escape of the air trapped within the concaves of said beaters which will permit said beaters to become filled with water. 100 As the yoke 27 begins its upward movement it will first release the increased tension upon the springs 37 which will permit the springs 40 to close the valves upon their seats thereby trapping the water which 105 has been forced upward into the concaves so that the further upward movement of the yoke carrying with it the beaters will cause said beaters to create a suction upon the clothes drawing water therethrough, thus 110 greatly facilitating the removal of the dirt which has been previously loosened by the pounding action of the beaters. The ratchet mechanism for intermittently revolving the actuating rod 14 is so timed 115 that during a portion of the upward stroke thereof said beaters are given a limited rotary movement which will tend to revolve the clothes within the receptacle since the beaters during this portion of the upward 120 stroke will be in contact with said clothes. This timing of the ratchet mechanism is also so timed as to continue the limited rotary movement of the beaters during a portion of their downward stroke, thus bringing 125 them in a position to contact with the clothes at a different point from their previous point of contact, and a continuation of this process will bring said beaters in contact with all portions of the clothes being 130

washed while at the same time giving the clothes a slight rotary motion within the receptacle which latter will stir up the contents of the receptacle thereby more effectually accomplishing the process of washing.

The outer end of the shaft 4 carries a clutch 46 of any suitable construction for connecting this shaft with an electric or other motor 47. This shaft may also carry a belt 10 wheel 48 by which power may be applied to the machine through a belt from any suitable source.

The outer end of the shaft 7 has a bevel gear 49 which meshes with a corresponding gear 50 upon the lower end of the vertical shaft 51 journalled in suitable bearings 52, and the upper end of this shaft has mounted thereon a sleeve 53 in such manner as to turn therewith while having a limited sliding movement thereon, and upon each end of this sleeve is secured a bevel gear 54 adapted to mesh with the bevel gear 55 secured upon the outer end of the shaft 56 for actuating the rolls 57 and 58 of a suitable wringer 59 mounted upon the receptacle 1.

An outlet pipe 60 is provided for drawing off the water from the receptacle when the washing has been completed.

Of course I do not wish to be limited to the exact details of construction as herein shown as these may be varied within the limits of the appended claims without departing from the spirit of my invention.

Having thus fully described my invention, what I claim as new and useful is:—

1. In a washing machine of the character described, the combination of a receptacle, an actuating rod projecting through the bottom

of said receptacle, a stationary tube in which said rod is adapted to reciprocate and revolve, a pair of beaters connected together by a cross bar, said bar being so mounted upon said tube as to reciprocate and rotate thereon, a yoke adjustably attached to the actuating rod, means for reciprocating said rod, means for intermittently revolving the rod, valves for closing upon valve seats formed in the beaters, valve stems carrying said valves and extending through the outer ends of the yoke, springs interposed between the valves and the yoke, washers carried by the outer ends of the valve stems, and springs interposed between the ends of the yoke and said washers.

2. In a washing machine of the character described, a receptacle, a tube mounted in said receptacle, a pair of beaters so mounted upon said tube as to be capable of rotation and reciprocation thereon, valves adapted to close upon valve seats formed in the beaters, valve stems carrying said valves, an actuating rod fitted to slide and rotate within the tube, a yoke adjustably attached to the actuating rod, hubs formed upon the outer ends of the yoke through which the valve stems pass, springs interposed between the valves and the outer ends of the yoke whereby the valves may be opened by the arresting of the downward movement of the beaters, a ratchet secured to the lower end of the actuating rod, means for actuating said ratchet, step by step for revolving the rod, and means for reciprocating the rod.

In testimony whereof, I have hereunto affixed my signature.

PETER C. FRITZ.
